GILLES HOLST AND ALBERT BOUWERS, OF EINDHOVEN, NETHERLANDS, ASSIGNEES
TO N. V. PHILIPS' GLOEILAMPENFABRIEKEN, OF EINDHOVEN, NETHERLANDS.

ELECTRIC DISCHARGE TUBE.

Application filed August 25, 1925, Serial No. 52,398, and in Netherlands November 17, 1924.

This invention relates to an improvement in or modification of that described in specification No. 5,108 concerning electric discharge tubes, and more particularly discharge tubes in which during the operation very high tensions occur as, for example, tubes for Röntgen-therapeutics.

According to the prior specification members of a discharge tube between which during the operation a very high potential difference occurs, are connected to each other by a wall which consists of parts of insulating material alternating with parts of conductive material. By arranging the parts of conductive material in such a manner that a desired potential can be impressed on them, it is made possible to divide the total potential difference occurring during the operation in the discharge tube, equally over the insulating parts, which offers the advantage that the total insulating length of these parts together can be materially smaller than the insulating length of one insulating piece would have to be. According to the prior specification the wall which connects the members between which during the operation a very high potential difference occurs, for example, electrodes of the discharge tube, may form wholly or partly the outer wall of the discharge tube.

In discharge tubes according to the prior specification of the latter kind it may happen that undesired discharges occur between the electrodes. If, for example, the electrodes have surfaces lying close to each other so that even when supplying a very high tension there does not occur any ionization between these surfaces, it may yet occur that between other parts of the electrodes or along other paths undesired discharges are produced. In order to obtain a sufficient insulation along the outer wall, this wall and therefore, also, the inner room must have dimensions which are a great many times larger than the distance between the said surfaces of the electrodes so that discharge paths of materially larger length can be formed, in which case ionization may occur.

According to the present invention, in order to obviate this disadvantage conductive walls are connected to the conductive parts of the outer wall in such a manner that

that part of the inner room of the discharge tube in which undesired discharges might occur, is divided into a series of discharge paths.

According to this invention, the interior space of the discharge tube is, preferably, divided into a number of compartments which are bounded not only by the insulating and conductive parts of the outer wall, or by the electrodes, but principally by partitions which are connected to successive conductive parts of the outer wall of the discharge tube.

If that part of the outer wall which is composed of insulating and conductive parts, is constituted by an oblong vessel, the partitions may extend on either side towards the middle of said vessel, the free ends of the partitions, preferably, overlapping each other.

The present invention may be applied inter alia to X-ray tubes comprising an incandescent cathode. If in this case the incandescent cathode is arranged within a metal vessel which is separated from the anticathode by an insulation capable of resisting the total operating voltage, and which on the anticathode side is narrowed to an aperture for the passage of the cathode rays and if that part of the anticathode which is struck by the cathode rays, is located in or near said aperture, the anticathode may be connected according to the present invention to a conductive wall surrounding at least partly the metal vessel in which the incandescent cathode is arranged. Also the anticathode may be connected to a conductive wall which surrounds a considerable portion of the length of the glass tube to the end of which the anticathode is secured.

According to this invention, the partitions which may extend on either side to the middle of the X-ray tube, may preferably end in or near a plane at right angles to the axis of the tube and intersecting the metal vessel in which the incandescent cathode is arranged.

When operating discharge tubes according to the present invention the conductive parts of the outer wall are preferably given such potentials that the total potential difference occurring between the electrodes is

equally divided over the insulating parts of the outer wall.

The accompanying drawing illustrates, by way of example, an incandescent cathode X-ray tube to which the invention is applied and also illustrates diagrammatically the insulation for operating said tube.

The X-ray tube illustrated is provided with an anticathode 1 the edge of which is 10 hermetically sealed to the end of a glass tube 2. The anticathode is hollow in order that it may be cooled by a suitable cooling medium supplied by a tube 3 secured in the anticathode. An incandescent cathode 4 is 15 arranged in a metal vessel 5 mounted coaxially with the anticathode and having on the side of the latter an aperture 6 for the passage of the cathode- and X-rays. The edge of the metal vessel 5 is hermetically 20 sealed to a glass tube 7 which passes into a conical part 8 in which is provided a window 9 in order to hermetically close the discharge tube and to allow the X-rays to pass. One end of the incandescent cathode 25 4 is electrically connected to the metal vessel 5 whereas the pole wire supporting the other end of the filament, is insulated from the metal vessel by a bead 10 of quartz or any other insulating material. A leading-in 30 wire 12 for this end of the filament and a leading-in wire 11 which is connected to the metal vessel, pass through tubes 14 and 13 of insulating material, for example, of glass, in order to prevent the two leading-in wires 35 from being short-circuited and from coming into contact with the metal walls in the tube. The ends of the glass tubes 2 and 8 are hermetically sealed to a cylindrical vessel consisting of metal rings 16, 17, 18, 19 and 40 20 and of glass parts 21, 22, 23 and 24 which are hermetically sealed to the said metal rings. To the metal rings 16, 17, 18 and 20 are connected metal partitions 25, 26, 27 and 28 which extend on either side to the middle 45 of the X-ray tube. A cylindrical wall 29 which surrounds the glass tube 2, is connected to the anticathode, and a cylindrical metal wall 30 starting from the anticathode, extends downwardly over the metal vessel 5. 50 When operating the discharge tube, a source of alternating current is brought via a regulable resistance 34 into connection with a primary winding 35 of a heating current transformer and through a regulable 55 resistance 40 with a primary winding 36 of a high tension transformer by closing a bipolar switch 33. A secondary winding 37 of the heating current transformer is connected to the incandescent cathode 4 by means of the 60 leading-in wires 11 and 12 whereas a secondary winding 38 of the high tension transformer is connected at its ends to the anti-cathode 1 and to the metal vessel 5 and is divided into six equal parts, branches to the 65 metal rings 16-20 being provided so that

the total potential difference is equally divided among the insulating parts of the outer wall of the tube. The middle of the secondary winding which is connected to the ring 18, is at the same time in connection with an iron core 39 of the transformer which is earthed. 70

During the operation of the X-ray tube which is either highly evacuated or has a gaseous filling consisting of hydrogen or helium at a pressure lying, for example, between 0.0006 mm. and 0.01 mm. of mercury, the incandescent cathode 4 emits electrons which under the influence of an electric field are drawn to the anticathode where they generate X-rays. Owing to the particular shape of the vessel 5, the electrons can strike only a small surface of the anticathode mirror. The X-rays generated leave the tube through the window 9 and for the other part are absorbed by the metal partitions. By means of the partitions the interior space of the X-ray tube is divided into annular compartments A, B, C, D, E and F and a chamber G which directly surrounds the two electrodes. The annular chambers A-F are bounded not only by the metal rings 16-20 and by insulating walls but principally by partitions which are connected to successive rings. Consequently in each compartment 95 there principally occurs the potential difference which also occurs between the successive rings. If, for example, in the X-ray tube illustrated the total operating voltage is 300,000 volts the potential difference principally occurring in each compartment will be but 50,000 volts so that the possibility that undesired discharges are produced is considerably diminished by providing the partitions. Near the open ends of the compartments B, C, D and F end each time partitions which have a higher potential difference relatively to the walls of each compartment than the potential difference occurring between the said walls. This offers, 100 however, no difficulty as the distances between the parts having a higher potential difference are small. It is obvious that in the compartment G there occur very high potential differences but they cannot have any detrimental influence as the dimensions of this compartment are but small. 105

The penetration of electrons is further prevented by the fact that the partitions overlap each other. 110

The partitions offer the incidental advantage that X-rays which do not belong to the active beam, can be absorbed. 115

The metal rings 16-20 may advantageously be made of chrome iron of suitable 120 composition, as this material can be sealed very well to glass, is not porous and is easily deprived of occluded gases. For constituting the partitions as well as the wall of the vessel 5 and the walls 25-30 may, prefer- 125 130

ably, be chosen a material which is easily deprived of occluded gases and which absorbs X-rays. For example for constituting these walls chrome iron may also be used.

5. What we claim is:

1. An electric discharge tube in which that part of the outer wall of the tube which connects electrodes receiving during the operation a high potential difference, consists of parts of insulating material alternated by parts of conductive material, characterized in that conductive partitions are connected to the conductive parts of the outer wall in such a manner that that part of the interior space of the discharge tube in which undesired discharges might occur, is divided into a series of discharge paths.

2. A discharge tube according to claim 1, characterized in that the interior space is divided in a number of compartments which are bounded not only by the insulating and conductive parts of the outer wall and some by the electrodes, but principally by partitions which are connected to successive conducting parts of the outer wall of the discharge tube.

3. A discharge tube according to claim 1, characterized in that that portion of the outer wall which is composed of insulating and conductive parts, is an oblong vessel, the partitions extending on either side to the middle of the said vessel.

4. A discharge tube according to claim 1, characterized in that that portion of the outer wall which is composed of insulating and conducting parts, is an oblong vessel, the partitions extending on either side to the middle of the said vessel, and the free ends of the partitions overlap each other.

5. An incandescent cathode X-ray tube according to claim 1, in which an incandescent cathode is arranged within a metal vessel which is separated from the anticathode by an insulation capable of resisting the total operating voltage, and which on the side of the anticathode is narrowed to an aperture for the passage of the cathode rays, that part of the anticathode which is struck by the cathode rays, being located in or near said aperture, characterized in that to the anticathode is connected a conductive wall which surrounds at least partly the metal vessel in which the incandescent cathode is arranged.

6. An incandescent cathode X-ray tube according to claim 1, in which an incandescent cathode is arranged within a metal vessel which is separated from the anticathode by an insulation capable of resisting the total operating voltage, and which on the side of the anticathode is narrowed to an

aperture for the passage of the cathode rays, that part of the anticathode which is struck by the cathode rays, being located in or near said aperture, characterized in that to the anticathode is connected a conductive wall which surrounds at least partly the metal vessel in which the incandescent cathode is arranged, and also characterized in that to the anticathode is also connected a conductive wall which surrounds the glass tube to the end of which the anticathode is secured over a considerable portion of its length.

7. An incandescent cathode X-ray according to claim 1, in which an incandescent cathode is arranged within a metal vessel which is separated from the anticathode by an insulation capable of resisting the total operating voltage, and which on the side of the anticathode is narrowed to an aperture for the passage of the cathode rays, that part of the anticathode which is struck by the cathode rays, being located in or near said aperture, characterized in that to the anticathode is connected a conductive wall which surrounds at least partly the metal vessel in which the incandescent cathode is arranged, the anticathode and the metal vessel with the aperture for the passage of the cathode rays being coaxially arranged, said tube being further characterized in that the partition extending on either side to the middle of the tube and in a plane substantially at right angles to the axis of the tube and cutting the metal vessel in which the incandescent cathode is arranged.

8. An installation for operating a discharge tube according to claim 1, characterized in that the conductive parts of the outer wall are given such potentials that the total potential difference occurring between the electrodes, is equally divided over the insulating parts of the outer wall.

9. A discharge tube according to claim 1, characterized in that the interior space is divided into a number of compartments which are bounded not only by the insulating and conducting parts of the outer wall and some by the electrodes, but principally by partitions which are connected to successive conducting parts of the outer wall of the discharge tube, and further characterized in that that portion of the outer wall which is composed of insulating and conductive parts, is an oblong vessel, the partitions extending on either side to the middle of the said vessel.

In testimony whereof we affix our signatures, at the city of Eindhoven, this 10th day of August, 1925.
